TREATMENT WITH LIQUIDS OF METAL ARTICLES, ESPECIALLY PLATES

John Curran, Cardiff, Wales

Application June 29, 1940, Serial No. 343,301
In Great Britain June 28, 1939

2 Claims. (Cl. 266—7)

This invention relates to the treatment with liquids, for instance pickling, washing, delacquering and/or degreasing, of metal articles, especially plates.

Hitherto metal plates have been pickled by dipping them individually into a bath of pickling acid, or by immersing a batch or pack of plates, supported in a basket, in a bath of pickling acid and agitating the basket by vertical reciprocating movements. It has also been proposed to spray with pickling acid plates suspended by one edge from a conveyer, the sprays being directed on to the surfaces of the plates.

An object of the invention is to provide an improved method of treating plates with liquids which is both economical and efficient.

The invention comprises a method of subjecting metal plates to treatment with jets of a liquid, wherein the jets are directed upon the upper edges of a pack of plates situated in, or moving through, a vertical position or a position sufficiently near the vertical to enable the plates to be separated by the jets.

The term "plates" is to be understood to include sheets, strips and the like.

The liquid reaches the surfaces of the plates, in this method, in the form of streams rather than as a spray, and the force of the jets tends to separate the plates and facilitate the flow of the liquid to all parts of the plate surfaces.

The invention also comprises apparatus adapted to carry out the aforesaid method, which comprises a rotor divided by radial partitions into a number of sectoral compartments each adapted to receive the articles to be treated, and at least one row of nozzles situated adjacent to the periphery of the rotor and in or nearly in the vertical plane containing the axis of the rotor, the nozzles being connected with means for supplying the treating liquid.

The invention may be applied with advantage to pickling sheets or plates of steel preparatory to tinning, or the commercial mild steel sheet known as "backplate" preparatory to its final annealing.

The invention is illustrated by way of example in the accompanying drawings, in which:

Fig. 1 is a side elevation and

Fig. 2 is a front elevation of apparatus for pickling metal plates.

The rotor is constructed of a hub 1 on which are fixed discs 2 held firmly in position by bolts 3 and each carrying a number of radial rods 4. The rotor is mounted on a shaft 5 adapted to rotate in bearings 6 and is driven by a motor (not shown) through gears 7. The rods 4 divide

the rotor into sectoral compartments each of which, as the compartment passes the position 8 in Fig. 1, receives from the conveyer 14 a pack of plates, the rotor being supposed to rotate clockwise. As the rotor turns, the pack of plates resting on the rods 4 and discs 2 is brought under the pipes 9 each of which has a row of nozzles and is fed with acid under pressure by means of a pump 10 which sucks acid from the sump 11 and delivers it by way of a pipe 12 to a header 13 with which the pipes 9 are connected.

The jets of acid projected from the nozzles in the pipes 9 impinge on the edges of the plates, and as the plates approach the vertical position they are separated by the jets, aided by gravity. After the acid has poured over the plates, pickling them and washing away the scale, it flows back into the sump 11.

The conveyer 14 consists of a number of endless ropes, preferably of rubber, which pass over sheaves 15 situated in the spaces between the rods 4. The plates are discharged by gravity from the compartment passing the position 16 in Fig. 1, if desired on to a suitable conveyer (not shown). If desired, a conveyer similar to the conveyer 14 may be provided to pick up the plates and remove them from the compartment 17. Alternatively, a single conveyer may perform the functions both of charging and discharging the machine. The conveyer may be divided into any suitable number of sections which pass between the rods and are carried by sheaves or sprockets situated at any convenient distance from the rotor. If necessary, the conveyer may be supported by sheaves or sprockets mounted on the hub 1.

In the example shown in the drawings, the rods 4 in effect form a number of radial partitions which divide the rotor into sectoral compartments. If desired, each set of rods forming a partition may be replaced by a radial plate; the compartments would then be adapted to hold articles of smaller dimensions than could be held by the partitions formed of rods.

Liquids other than acid, for instance washing, degreasing or delacquering liquids, may, if desired, be projected from the pipes 9.

I claim:

1. Apparatus for subjecting metal plates to treatment with jets of liquid, which apparatus comprises a rotor divided throughout the extent of its periphery by radial partitions into a number of sectoral compartments each adapted to freely receive a plurality of plates to be cleaned and bounded inwardly by the hub of the rotor which affords a support for the edges of the packs

of plates at the inner ends of the partitioned compartments, and at least one row of nozzles situated adjacent to the periphery of the rotor and substantially in the vertical plane containing the axis of the rotor, the nozzles being connected with means for supplying the treating liquid downwardly along and against the upper edges of the pack of plates in the form of jets from said row of nozzles to enable the plates to be separated by said row of jets to facilitate the flow of liquid to all parts of the plate surfaces, a conveyor adapted to deposit the plates in each compartment of the rotor before that compartment passes under the nozzles and a conveyor adapted to remove the plates from each compartment after that compartment has passed under the nozzles, each of said radial partitions consisting of a number of rods projecting radially from the hub of the rotor and the said conveyors consisting of a number of endless flexible members such as 20 chains or ropes which pass between the said rods.

5 10 15 20

2. Apparatus for subjecting metal plates to treatment with jets of a liquid, such apparatus comprising a rotor mounted for continuous rotation and divided throughout the extent of its periphery by radial partitions into a number of sectoral compartments, each adapted to freely receive a plurality of metal plates to be cleaned, and bounded inwardly by the hub of the rotor which affords a support for the metal plates at their inner edges, and at least one row of nozzles situated adjacent to the periphery of the rotor and substantially in the vertical plane containing the axis of the rotor, the nozzles being connected with means for supplying the treating liquid through the said row of nozzles downwardly in the form of streams or jets along and against the upper edges of the plates to enable the plates to be separated by the row of jets to facilitate the flow of liquid to all parts of the plate surfaces.

JOHN CURRAN.
